UNITED STATES PATENT OFFICE.

ALBERT L. BROWN, OF LITTLE ROCK, ARKANSAS.

DISCHARGE-VALVE.

1,080,322.

Specification of Letters Patent.

Patented Dec. 2, 1913.

Application filed November 19, 1912. Serial No. 732,327.

To all whom it may concern:

Be it known that I, ALBERT L. BROWN, a citizen of the United States, and a resident of Little Rock, in the county of Pulaski, and State of Arkansas, have invented certain new and useful Improvements in Discharge-Valves, of which the following is a full, clear, and exact specification.

This invention relates to valves especially designed to be employed in ammonia compressors for controlling the discharge of the compressed gas.

One object of the invention is to provide for regulating the opening or lifting of the valve, and another object is to cushion said valve in opening and closing, whereby the valve seat will not be hammered out of shape or broken as has sometimes occurred in previous constructions.

20 Another object is to produce a valve structure capable of having its closing spring removed and another one inserted without taking off the head of the compressor or the cap of the valve.

25 Another object is to prevent the lubricating oil from carbonizing and causing the valve to stick open or closed, and still another object is to provide for the proper movement of the valve without allowing the high pressure gas to pass up around the sides of the valve to the interior of the cap where it would destroy the partial vacuum which is created in said cap when the valve moves to its seat and which serves to cushion said valve.

30 The invention will be first fully described in connection with the accompanying drawings which constitute a part of this specification, and then more particularly pointed out in the claims at the end of the description.

In the drawings, in which similar reference characters are used throughout to designate the same parts, Figure 1 is a central vertical section of an ammonia compressor embodying my improved valve structure, Fig. 2 is an enlarged central vertical section of the valve mechanism alone; Fig. 3 is a section taken on the line 3-3 of Fig. 2; Fig. 4 is a section taken on the line 4-4 of Fig. 2; Fig. 5 is a section taken on the line 5-5 of Fig. 2, and Figs. 6 and 7 are separate detail views of the concentric tubes for controlling the spring pressure and vacuum cushion for the valve, and for feeding the lubricant.

The compressor illustrated in Fig. 1 includes a cylinder A into which the gas enters from the bottom, a piston B arranged to be reciprocated in said cylinder and provided with a suitable suction valve (not shown), and a large valve C controlling the outlet of the gas from the cylinder. Said outlet valve C is arranged at the upper end of the cylinder above an inclined or curved seat D. In its vertical reciprocations said outlet valve is guided in a sleeve or collar E on the cylinder cap F which also carries the valve seat D. One or more split rings G are placed around the valve C for the purpose of guiding the same and preventing gas from passing between said valve and the sleeve E. Three of these rings are illustrated, the upper two being designed particularly for sealing purposes and the lower one for guiding the valve. Said valve C may be made hollow as shown, and provided with a cup or container H for a helical spring I which may be seated on a removable plug h in the lower end of the cup, and at the upper end of said spring there may be laid a plunger disk J having a screw threaded socket j in its upper surface, see Fig. 3.

The upper end of the sleeve or collar E is covered and sealed by a cap K through the top of which a tube L is screwed, said tube extending down into contact with the plunger disk J and up through the cover M of the compressor. The passage of the tube through the cover of the compressor is suitably packed, as at m. The portion of the tube arranged between the cover of the compressor and the cap of the guiding sleeve, is provided with one or more perforations l' extending or leading in different directions as shown. The portion of the tube within the sleeve is also perforated as at l'.

A smaller tube N is arranged concentrically within the tube L and spaced therefrom so as to leave an uninterrupted passage between them. This passage is closed at the top of the outer tube by a plug P having a packing nut O. The inner tube extends up through said nut and carries at its upper end an oil cup Q from which oil is fed through said inner tube, the lower end portion of the outer tube, and the perforations l' in the latter to the spring container and the inner surface of the sleeve on which the packing and guiding rings G slide as the valve reciprocates. The bore in the lower

end of the outer tube is restricted below the inner tube to form a seat l^2 for the lower end of said inner tube. By reason of screw connection n between the inner tube and the plug P , said tube may be adjusted vertically to vary the size of the space between its lower end and its seat, thereby controlling the passage of the gas from above the cylinder cap F to the interior of the sleeve E when the valve C is closed and consequently regulating the degree of vacuum created for cushioning said valve.

In operation, when the piston B is on the up stroke as illustrated in Fig. 1, the compressed gas above it forces the valve C open against the influence of the spring I so that said gas passes as indicated by the arrows through the valve seat, and openings f in the cylinder cap F to the gas outlet. Some of the gas above said cap F will find its way into the sleeve E via the inlet passages l , the passage between the two concentric tubes, and gas outlet passages l' . When the piston moves on its down stroke, the gas in the sleeve becomes rarefied by reason of the restricted inlet passages being incapable of supplying gas fast enough to fill the space vacated by the valve, so that a partial vacuum is formed in the sleeve which cushions the downward movement of said valve and prevents the same from hammering its seat out of shape.

It will be observed that the oil is fed to the interior of the sleeve E where it is not subjected to the direct action of the compressed gas passing through the valve seat and cylinder cap. Consequently, the oil is not liable to become carbonized and cause the valve to stick as in previous constructions. Furthermore, the inner tube may be raised or lowered to regulate the degree of vacuum in the sleeve on the down stroke of the valve without interfering with the feeding of the oil, for the reason that the bore in said inner tube always remains in vertical alignment with the restricted bore in the lower end portion of the outer tube.

Another important advantage of the present construction as compared with previous ones, resides in the fact that the spring I for cushioning the up stroke of the valve and overcoming the partial vacuum on its down stroke, may be replaced, when necessary or desirable without removing the cover M or taking apart the valve and cylinder cap. In order to take out the spring in the present structure, it is only necessary to screw out the tube L , and insert a screw threaded rod or eye-bolt which may be screwed into the socket j in the plunger disk J for removing the latter, whereupon a hook may be engaged with the spring for lifting it out. A new spring may then be dropped into place, the plunger disk J replaced, and the tube screwed back into position, with

very little trouble and practically no waste of time.

It is obvious that changes may be made in the details of construction of the devices as herein shown and described without departing from the spirit or sacrificing the advantages of the invention. It should, therefore, be understood that the invention is not limited to such details but is to be broadly construed as set forth in the claims.

Having thus described my invention what I claim as new and desire to secure by Letters Patent of the United States is:

1. In a compressor, the combination with a cylinder, of a reciprocating discharge valve, a sleeve for guiding the valve, a cap on said sleeve, a removable member extending above the top of the compressor and down into said sleeve, said member fitting said cap and having a restricted passage opening above and below the cap, whereby said valve is cushioned as it moves to its seat by the formation of a partial vacuum in the sleeve behind the valve.

2. In a compressor, the combination with a cylinder, of a reciprocating discharge valve having a spring container in its upper end, a spring in said container, a sleeve for guiding the valve, a cap on said sleeve, and a removable member extending from above the top of the compressor down into said sleeve and forming an abutment for the spring.

3. In a compressor, the combination with a cylinder, of a reciprocating discharge valve, a sleeve for guiding the valve, the latter having an air-tight sliding joint with the sleeve, a cap on said sleeve, and a removable tubular member providing a restricted passage from the interior of the sleeve above the valve, whereby said valve is cushioned as it moves to its seat by the formation of a partial vacuum in said sleeve.

4. In a compressor, the combination with a cylinder, of a reciprocating discharge valve, means for guiding said valve, and a removable tubular member extending from above the top of the compressor into said guiding means for feeding oil to said valve from outside the cylinder.

5. In a compressor, the combination with a cylinder, of a reciprocating discharge valve, a sleeve for guiding said valve, and a removable member extending above the top of the compressor and down into said sleeve for feeding oil from above the cylinder to the interior of said sleeve.

6. In a compressor, the combination with a cylinder, of a reciprocating discharge valve, a sleeve for guiding said valve, a cap for said sleeve, a removable tube extending from above the top of the compressor into said sleeve for feeding oil to the valve, and means for admitting a limited quantity of gas to the sleeve for creating a partial

vacuum in said sleeve when the valve moves to its seat.

7. In a compressor, the combination with a cylinder, of a reciprocating discharge valve, a sleeve for guiding said valve, a cap for said sleeve, a tube extending through and fitting in said cap and provided with a restricted passage therein forming an annular shoulder, another tube arranged within and spaced from the inner wall of the first tube, said inner tube being adjustable to and from the shoulder in the outer tube, and means for feeding oil through the inner tube, said outer tube having restricted openings above and below the cap for admitting gas to the interior of the sleeve, the openings below the cap being also below the annular shoulder, whereby the adjustment of the inner tube will control the size of the inlet passage to the sleeve.

8. In a compressor, the combination with a cylinder, of a reciprocating discharge valve, a sleeve for guiding said valve, a cap for said sleeve, a tube extending through and fitting in said cap and provided with a restricted passage therein forming an annular shoulder, another tube arranged within and spaced from the inner wall of the first tube, said inner tube being adjustable to and from the shoulder in the outer tube, and means for feeding oil through the inner tube, said outer tube having restricted openings above and below the cap for admitting gas to the interior of the sleeve, the openings below the cap being also below the annular shoulder, whereby the adjustment of the inner tube will control the size of the inlet passage to the sleeve, the restricted passage in the outer tube being arranged in alignment with the passage in the inner tube so that the adjustment of said inner tube will not interrupt the passage of the oil to the sleeve.

9. In a compressor, the combination with a cylinder, of a reciprocating discharge valve having a spring container, a spring

in said container, a sleeve for guiding said valve, a cap for the sleeve, a removable tube of greater diameter than the spring constituting an abutment for the latter, and another tube arranged inside of the first tube and adapted to feed oil to the valve, said outer tube having openings above and below the cap for admitting a limited quantity of gas to the sleeve.

10. In a compressor, the combination with a cylinder, of a reciprocating discharge valve having a spring container, a spring in said container, a sleeve for guiding said valve, a cap for the sleeve, a removable tube of greater diameter than the spring constituting an abutment for the latter, and another tube arranged inside of the first tube and adapted to feed oil to the valve, said outer tube having openings above and below the cap for admitting a limited quantity of gas to the sleeve, and means for adjusting said inner tube whereby the size of the gas inlet passage to the sleeve is regulated.

11. In a compressor, the combination with a cylinder, of a reciprocating discharge valve having a spring container, a spring in said container, a sleeve for guiding said valve, a cap for the sleeve, a removable tube of greater diameter than the spring constituting an abutment for the latter, and another tube arranged inside of the first tube and adapted to feed oil to the valve, said outer tube having openings above and below the cap for admitting a limited quantity of gas to the sleeve, and means for adjusting said inner tube whereby the size of the gas inlet passage to the sleeve is regulated without interrupting the passage of the oil to the valve.

In testimony whereof I have signed my name to this specification in the presence of two attesting witnesses.
